UNITED STATES PATENT OFFICE.

FRANCIS C. MERTZ AND GEORGE E. MERTZ, OF PORT CHESTER, NEW YORK.

FAN ATTACHMENT FOR ROCKING-CHAIRS.

SPECIFICATION forming part of Letters Patent No. 651,721, dated June 12, 1900.

Application filed November 2, 1899. Serial No. 735,610. (No model.)

To all whom it may concern:

Be it known that we, FRANCIS C. MERTZ and GEORGE E. MERTZ, citizens of the United States, and residents of Port Chester, in the county of Westchester and State of New York, have invented a new and Improved Fan Attachment for Rocking-Chairs, of which the following is a full, clear, and exact description.

10 Our invention relates to an improvement in devices adapted for attachment to rocking-chairs and to be used for operating fans.

Our invention comprises the novel features hereinafter described and claimed.

15 Reference is to be had to the accompanying drawings, forming a part of this specification, in which similar characters of reference indicate corresponding parts in all the figures.

Figure 1 is a sectional elevation of a rocking-chair having our device attached thereto. Fig. 2 is a side elevation of the operating parts of our device. Fig. 3 is a sectional elevation of the same, taken oppositely to the view shown in Fig. 2. Fig. 4 is a sectional elevation of the operating mechanism of our device, taken at right angles to that of Fig. 3. Fig. 5 is a side elevation of a modified construction, and Fig. 6 is a detail sectional view taken on the line 6-6 of Fig. 5.

20 The object of our invention is to produce a device which may be attached to any rocking-chair and which is adapted by the act of rocking the chair to rotate a set of fans mounted to turn upon the chair, said operating mechanism being so constructed as to assure a steady and continuous rotary movement of the fans by the intermittent movement of the rocker. This result is secured by the insertion of a spring between the operating mechanism and the fan, said spring being wound up by the movement of the rocker and running down as the fan-carrying shaft is turned.

25 The operating mechanism is mounted upon a frame which has a flange or plate A, adapted to be secured along one side of the rocker. This plate has flanges a, adapted to bear upon the upper surface of the rocker, and thus to securely hold the frame in place. An upward extension of said frame forms a case A', within which are mounted the spring and the

gears by which action is communicated from the spring to the fan-carrying shaft K.

Extending centrally through the case A' is a shaft B, which is journaled in the sides of the case. The spring H, which is placed within this case and one end of which is secured to the shaft B, is a coiled spring of that character commonly used in clocks and is of such a size as to furnish the proper amount of power for the purpose desired. The spring lies within the hollow formed at the back of the bevel-gear G, having flanges G', which surround the spring, the outer end of the spring being secured to the gear. The gear meshes with a bevel-pinion I, secured to the lower end of a short shaft I, extending through suitable bearings in the upper side of the case A'.

30 To the upper end of the shaft I' is secured one-half of a coupling, the outer end of which consists of a hook J, which has a narrow opening at one side adapted to receive the end of a similar hook J', secured to the lower end of the shaft K. By this means a flexible joint is provided, which enables the shaft K to be smoothly turned whether it lies in exact alignment with the shaft I' or not.

35 The outer end of the shaft B is supported in one end of an arm C', which extends from the outer end of a boss C, secured to or formed as a part of the lower portion of the frame A. Upon the upper end of the arm C' is pivotally secured one end of a detent or friction-dog f', the outer end of which engages the inner periphery of the rim of a friction-wheel F upon the shaft B outside of the case A', said dog being held in engagement with the rim of the wheel by means of a spring f''. (See Fig. 2.) This dog will permit the friction-wheel to be freely turned in one direction, but will engage it and prevent its turning in the opposite direction.

40 Loosely mounted upon the shaft B and between the case A' and the friction-wheel F is a pinion E, which meshes with a toothed segment D', which is secured to or formed as a part of the arms D, which are pivotally mounted upon the boss C. One end of the segment-bar D' is carried downward and is provided with a roller d, adapted to rest upon the floor. Surrounding the boss C, upon

which the arms D are pivoted, is a spirally-coiled spring M, one end of which engages the arms D and the other end of which engages the arm C' of the frame, said spring serving 5 to hold the end of the segment-bar D', which carries the roller d, down upon the floor.

Upon one side of the pinion E is mounted a friction-dog f, which is similar in construction to the dog f', previously described, and 10 which engages the friction-wheel F to turn it when the pinion E is turned in one direction, but which is released therefrom without turning the same when the pinion is turned in the opposite direction. The dog f is pressed on 15 by a spring f². (See Fig. 2.)

Upon the upper portion of the frame or the casing A' is secured an arm L, adapted to be secured to one of the legs of the rocker, thus firmly securing the device in place.

20 The operation of our device is as follows: Beginning with the position shown in Fig. 1, if the chair be rocked backward the segment-bar D' will turn the pinion E, which in turn, by means of the friction dog or clutch f, will 25 engage and turn the friction-wheel F, and this wheel being secured to the shaft B will wind up the spring H. The backward movement of the shaft B is prevented by means of the dog f'. As soon as the strain upon the 30 spring H is sufficient to overcome the resistance of the mechanism and the fans O the fans will be turned, the speed at which the fans will turn depending upon the tightness with which the spring H is coiled. As the 35 speed of operation of the rocker increases the spring H will be coiled more tightly and the fans O will be turned more rapidly.

It is ordinarily intended that the device when in operation will have the spring H 40 partly coiled up, so that irregularities in the rocking of the chair will be compensated for by the spring, the same maintaining a steady operation of the fan even if the rocking of the chair be momentarily stopped. The upper end of the rod K, which carries the fans, 45 may be secured to the chair by means of an ordinary screw-eye, as shown at k.

In Figs. 5 and 6 a modified construction is shown in which two segment-bars D' and D² are 50 used, each of said bars acting upon separate pinions E and E', as shown in Fig. 6, and being provided with friction-dogs f³ and f⁴, adapted to engage the friction-wheel F. In 55 this form of construction the movement of the rocker forward as well as backward will serve to wind up the spring. With this form of construction the detent or friction-dog f', described in connection with the construction shown in Figs. 2 and 3, will not be necessary, 60 as one or the other of the friction-dogs f³ and f⁴ will be in operation to prevent backward rotation of the shaft. In this form of construction a more powerful spring than that M (shown in Fig. 4) will be required, as this 65 spring must overcome the friction of the parts and the strain of the spring H. For this purpose a spiral coiled spring M', such as

shown in Fig. 5, is used and is connected at one end to an arm N, secured to the arms D, and at the other end to an arm N', which is 70 secured to the frame. By interposing the spring H, by which power is stored up, between the operating mechanism and the fan-shaft a steady and continuous rotation of the fans O may be secured even if the rocking is 75 temporarily stopped.

Having thus fully described our invention, we claim as new and desire to secure by Letters Patent—

1. A fan attachment for rocking-chairs, 80 comprising a fan-holding shaft, means for mounting the shaft upon the chair, a case and a spring therein, securable to the rocker of the chair, a gear secured to one end of the spring, a shaft secured to the other end of the 85 spring, a pinion engaging the gear and connected with the fan-holding shaft to turn it, a pinion having a clutch connection with the shaft, and a toothed segment-bar pivoted upon the chair to swing in engagement with 90 said last-mentioned pinion and having one end adapted to engage the floor, substantially as described.

2. A fan attachment for rocking-chairs, 95 comprising a fan-holding shaft, means for mounting the shaft upon the chair, a spring and its case securable to the bottom part of the chair, a gear secured to one end of the spring, a shaft secured to the other end of the 100 spring, a pinion engaging the gear, a swivel connection between said pinion and the fan-holding shaft to turn it, a pinion having a clutch connection with the shaft, and a toothed segment-bar pivoted upon the chair to swing in engagement with 105 said last-mentioned pinion and having one end adapted to engage the floor, substantially as described.

3. A fan attachment for rocking-chairs, 110 comprising a fan-holding shaft adapted to be mounted on the chair-back, an operating device comprising a power-storage spring, 115 swivel connections therefrom to the fan-holding shaft to turn it, an arm pivotally supported from the chair and adapted to engage the floor, and rotative clutch connection from said arm to the power-storage spring, substantially as described.

4. A fan attachment for rocking-chairs, 120 comprising a fan-holding shaft adapted to be mounted upon the chair, an arm or lever pivotally supported upon the chair, and adapted to engage the floor, a mechanism for converting the oscillations of said arm into rotary motion, and a power-storage spring interposed 125 between a rotating member of said mechanism and the fan-holding shaft, to turn the latter, substantially as described.

5. A fan attachment for rocking-chairs, 130 comprising a fan-holding shaft adapted to be mounted upon the chair, an arm or lever pivotally supported upon the chair and adapted to engage the floor, a spring acting upon the said arm to hold it downward or in engagement with the floor, a mechanism for con-

verting the oscillations of said arm into rotary motion, and a power-storage spring interposed between a rotating member of said mechanism and the fan-holding shaft, to turn the latter, substantially as described.

5 6. A fan attachment for rocking-chairs, comprising a fan-holding shaft adapted to be mounted upon the chair, an operating device comprising a power-storage spring, swivel connections therefrom to the fan-holding shaft to turn it, an arm pivotally supported from the chair and adapted to engage the floor, a spring acting upon said arm in opposition to the chair, and rotative clutch connection 15 from said arm to the power-storage spring, substantially as described.

7. A fan attachment for rocking-chairs, comprising a frame securable to the bottom part of the chair, a shaft journaled in said frame, a bevel-gear mounted to turn upon

said shaft, a spring connected at opposite ends to the shaft and gear, a pinion mounted to turn upon the shaft, a clutch-pulley secured to the shaft, a clutch-dog carried by the pinion and engaging the clutch-pulley to 25 turn it in one direction, a clutch-dog or detent engaging the pulley to prevent backward motion, an arm pivotally supported from the chair and adapted to bear upon the floor, a toothed segment carried by said arm and 30 engaging the pinion to turn it, a bevel-pinion meshing with the bevel-gear, and a flexible rotative connection between the shaft of said bevel-pinion and the fan-holding shaft, substantially as described.
